BABY'S BATH SEAT

William J. Black, Clearfield, Pa., assignor to Curtiss-Wright Corporation, a corporation of Delaware

Application October 11, 1956, Serial No. 43,331

Term of patent 7 years

(Cl. D15—1)

Fig. 1 is a top plan view of a baby's bath seat embodying my new design.

Fig. 2 is a front elevational view of the seat of Fig. 1.

Fig. 3 is a side elevational view of the seat of Fig. 1.

I claim:

The ornamental design for a baby's bath seat, as shown.
